PNEUMATIC FIGURE TOY OR SIMILAR ARTICLE

George Posner, Douglaston, N. Y., assignor to New York Merchandise Co., Inc., New York, N. Y.

Application April 20, 1954, Serial No. 30,105

Term of patent 3½ years

(Cl. D34—15)

Fig. 1

Fig. 2

Fig. 3

To all whom it may concern:

Be it known that I, George Posner, a citizen of the United States of America, residing at Douglaston, New York, have invented a new, original, and ornamental Design for a Pneumatic Figure Toy or Similar Article, of which the following is a specification, reference being had to the accompanying drawing, forming a part thereof.

Fig. 1 is a front elevational view of a pneumatic figure toy or similar article, showing my new design;

Fig. 2 is a fragmentary side elevational view thereof, a portion being omitted for convenience of illustration; and

Fig. 3 is a top plan view thereof.

I claim:

The ornamental design for a pneumatic figure toy or similar article, as shown and described.
